UNITED STATES PATENT OFFICE.

CHRIST RENNER, JR., OF INDIANAPOLIS, INDIANA.

THILL-COUPING.

SPECIFICATION forming part of Letters Patent No. 229,555, dated July 6, 1880.

Application filed February 27, 1880.

To all whom it may concern:

Be it known that I, CHRIST RENNER, Jr., of Indianapolis, in the county of Marion and State of Indiana, have invented a new and 5 useful Device for Taking Up Lost Motion and Preventing the Rattling of Thill - Irons, of which the following is a specification.

My invention relates to improvements in thill-irons, in which a plate for holding a rubber spring is swiveled to a screw-threaded stud having a head which operates in conjunction with the clip, the thill-iron, and lock-nut; and the objects of my improvement are, first, to afford facilities for the proper adjustment of the rubber spring against the shaft-iron to prevent rattling; second, to take up lost motion between the shaft-iron and coupling-bolt, also between the coupling-bolt and clip-iron.

20 I attain these objects by the mechanism illustrated in the accompanying drawings, in which—

Figure 1 is a perspective view of the entire device. Fig. 2 is a sectional view of the same; 25 and Fig. 3 is a detail view, in perspective, of the adjusting mechanism.

The clip A is provided with screw-threaded studs B B and a cross-bar, C, to secure the clip to an axle in the usual manner. The 30 clip also has forward-projecting lugs D D, between which the shaft-iron J is secured, also in the usual manner; but the lugs D D project more in front than those on ordinary clips, and the upper portion (marked E E) of 35 each is curved or hollowed out to allow more room for working the adjustable device located between them.

The adjustable mechanism consists of a screw-stud, L, with head F', on which the 40 lock-nut F operates. The front end of the screw L is turned down and fitted loosely in a hole formed in the block G, forming a swivel-joint, as shown at m in Fig. 3.

The rear end of the screw-threaded stud L 45 operates in a screw-threaded hole formed in the front part, A', of the clip A, between the forward-projecting lugs D D, so that when the stud L is revolved, as in the act of unscrewing it from the hole in the clip, the

block G is adjusted forward, and when the 50 stud is revolved, as in the act of screwing it up, then the block G is adjusted back, the nut F acting as a lock-nut to hold the stud L in position when adjusted.

H represents a rubber cushion located between the block G and that part of the shaft-iron J in which the bolt K is inserted.

The adjusting device, consisting of the screw-threaded stud L, with head F', lock-nut F, and swiveled block G, is first inserted 55 between the lugs D D. The stud L is then screwed home in the screw-threaded hole formed in the clip. The rubber cushion H is then placed between the flanges a a of the block G. The shaft-iron J is then inserted 60 between the jaws D D and secured by the bolt K. Should the bolt K or holes in which it is inserted become worn, all lost motion can be taken up by placing a wrench on the head F' and unscrewing the stud L, which 65 forces the rubber cushion tightly against the shaft-iron.

When the stud L has been adjusted sufficiently to prevent rattling and take up any lost motion, it is then secured in position by the 70 lock-nut F, which is screwed back so as to jamb against the face of the clip.

I am aware that prior to my invention thill-irons have been made with clips and projecting lugs, operating in conjunction with a 75 shaft-iron, a bolt, and a rubber cushion. I therefore do not claim such a combination, broadly; but

What I do claim as my invention, and desire to secure by Letters Patent, is—

1. In a thill-coupling, the adjustable device 85 consisting of the screw-threaded stud L, provided with lock-nut F and head F', having one end swiveled to the block G and its other end operating in a screw-threaded hole formed 90 in one side of the clip A, between the lugs D D, substantially as specified.

2. In a thill-coupling, the combination of the clip A, having forward-projecting lugs D D, curved or hollowed out on their upper 95 edges, as at E, and provided with a screw-threaded hole in the part A', between the lugs D D, the screw-threaded stud L, with head F'

and lock-nut F, the swiveled block G, the rubber cushion H, the shaft-iron J, and bolt K, as and for the purpose specified.

3. In a thill-coupling, the combination, in
5 the adjusting device, of the screw-threaded
stud L with head F, the swiveled block G, and
lock-nut F, as and for the purpose specified.

In testimony whereof I have signed my name
to this specification in the presence of two sub-
scribing witnesses.

CHRIST RENNER, JR.
